A tube bar for use in creating an item of permanent jewelry is described, involving a tube bar having a body comprising a precious metal, having a first end and a second end, a cavity extending into the first end, a through hole, perpendicular to the cavity, that passes from one side surface of the body to an opposite side of the body. The cavity extends into the body to a depth beyond the through hole, and the cavity is dimensioned to accept a terminal end of a Band. An item of permanent jewelry incorporating the tube bar and a Band is also described.

PERMANENT JEWELRY AND METHOD OF
MAKING SAME

FIELD OF THE INVENTION

This disclosure relates generally to jewelry and, more particularly, to permanent jewelry.

BACKGROUND

“Permanent” jewelry are items of jewelry, such as bracelets, bangles, anklets, necklaces, chokers and rings, that lack an opening or a clasp, toggle or closure and are sized so that, when on the wrist, ankle, neck or finger, they cannot be physically removed from the wrist over the hand, ankle over the foot, neck over the head or finger over the proximal interphalangeal joint, without damaging the item.

Permanent jewelry has become very popular.

Permanent jewelry is currently created by joining the ends of the bracelet, bangle, anklet or necklace using micro welding (micro TIG, laser micro or pulsed arc) techniques. To do so, however requires the components (chains, wires or jump rings) that will be joined to be very thin in order to ensure a solid connection is made. As a result, a drawback to permanent jewelry is that the components tend to be fragile, and can break easily.

It is difficult to use thicker components for permanent jewelry several reasons. First, the joining must necessarily be done while the jewelry is being worn. Micro welding (a form of spot welding) applies heat to fuse together the two pieces to be joined. Thus, to avoid burning the wearer, the joining process must be performed quickly, so thinner pieces make that possible. Second, to ensure a solid connection with thicker pieces, multiple welds must be done about the periphery of the joint area. This can be difficult on the underside of the jewelry item, both through physical placement and in a way that obtains a good connection. Third, with thicker components, the necessary micro welds become more visible and, by their very nature, are not aesthetically pleasing to look at.

In addition, micro welding requires skill and training to avoid using power that is too low or high and to ensure that the intended wearer does not get injured from the joining process.

Still further, permanent jewelry is often made available at temporary locations, such as fairs, exhibitions, etc., yet the machinery used to perform micro welding (e.g. welder, microscope or viewer, argon canister), are bulky and can be awkward or heavy for a permanent jewelry seller to carry around from place to place.

Finally, in order to be aesthetically pleasing, and in some cases have appropriate strength, it can be critical that the two ends to be micro welded be perfectly aligned. This also takes skill and practice.

There are presently no satisfactory solutions for the aforementioned issues individually or collectively.

SUMMARY

This disclosure describes solutions that provide significant advances in addressing the aforementioned problems.

One aspect of this disclosure involves an item of permanent jewelry including a Band including a first terminal end and a second terminal end, the first terminal end includes a through hole therein. The item of permanent jewelry further involves a tube bar having at least one through hole corresponding to the through hole of the first terminal end. The

2

first terminal end is located within a cavity of the tube bar such that the through hole of the first terminal end and through hole of the tube bar are aligned. The item of permanent jewelry also involves a pin, extending through the aligned through holes of both the Band and tube bar, wherein the pin is compressed on both sides of the aligned through holes such that the pin cannot slide out of the aligned through holes; and wherein the second terminal end of the Band is coupled to the tube bar such that a closed loop involving the Band and tube bar is formed.

Another aspect of this disclosure involves a tube bar for use in creating an item of permanent jewelry. The tube bar involves a body comprising a precious metal, having a first end and a second end; a cavity extending into the first end; a through hole, perpendicular to the cavity, that passes from one side surface of the body to an opposite side of the body. The cavity extends into the body to a depth beyond the through hole, and the cavity is dimensioned to accept a terminal end of a Band.

Yet another aspect of this disclosure involves an item of permanent jewelry. The item of permanent jewelry involves a Band and a tube bar. The band is connected to the tube bar by at least one crimped pin extending through both the tube bar and an end of the Band so that the Band and tube bar collectively form a closed loop about a part of a person of a size such that the closed loop cannot be slid off the person without damaging at least one of the Band, the tube bar or the crimped pin.

BRIEF DESCRIPTION OF THE DRAWINGS

This disclosure is further described in the detailed description that follows, with reference to the drawings, wherein the same reference numbers appearing in the various drawings and description designate corresponding or like elements among the different views, and in which:

FIG. 1 illustrates, in simplified form, an example of bangle bracelet for a wrist incorporating one aspect of the teachings herein;

FIG. 2 illustrates, in simplified form, a perspective view of another permanent jewelry component in accordance with the teachings herein, in the form of a tube bar;

FIGS. 3-6 respectively illustrate, in simplified form, for purposes of understanding, a top view, a right side view, a back view and a front view of the tube bar of FIG. 2;

FIGS. 7-12 illustrate, in simplified form, one example sequence for creating a permanent bangle bracelet using the Band of FIG. 1 and tube bar of FIG. 2;

FIG. 13 illustrates, in simplified form, an example of a permanent bangle bracelet created according to the teachings herein;

FIGS. 14-18 respectively illustrate, in simplified form, different views of a tube bar that includes one or more adornments raised above the surface of the tube bar;

FIGS. 19-24 respectively illustrate, in simplified form, different views of another tube bar that includes one or more adornments into (i.e., below) the surface of this tube bar;

FIGS. 25-32 illustrate, in simplified form, different views of yet another example of a type of tube bar containing one or more raised adornments;

FIGS. 33-39 illustrate, in simplified form, different views of yet another example of a tube bar that includes adornments;

FIG. 40 illustrates, in simplified form, one example 4000 illustrating a reverse version for creating an item of permanent jewelry according to the teachings herein;

FIG. 41 illustrates, in simplified form a cross section of the ends in FIG. 40 after they have been joined;

FIG. 42 illustrates, in simplified form, an example implementation involving a tube bar that only includes one through hole;

FIG. 43A illustrates, in simplified form an alternative example tube bar;

FIG. 43B illustrates, in simplified form another alternative example tube bar;

FIG. 43C illustrates, in simplified form yet another alternative example tube bar;

FIG. 44 illustrates, in simplified form, another example implementation of an item of permanent jewelry 4400 that can be created by applying the teachings herein;

FIG. 45 illustrates, in simplified form, yet another example implementation of an item of permanent jewelry that can be created by applying the teachings herein;

FIG. 46A illustrates, in simplified form, a top view of another example implementation of an item of permanent jewelry 4600 that can be created using a variant the foregoing;

FIG. 46B illustrates, in simplified form, a side view of the item of permanent jewelry of FIG. 46A;

FIG. 47 illustrates, in simplified form, an additional example variant implementation of a tube bar (only a portion of which is shown) suitable for use with a chain-type Band;

FIG. 48 illustrates, in simplified form, a top view of one representative example of how a chain-type Band can be attached to a tube bar;

FIG. 49 illustrates, in simplified form, a top view of another representative example of how a chain-type Band can be attached to a tube bar;

FIG. 50 illustrates, in simplified form, a representative example of an implementation variant that can be used in circumstances where the tube bar of FIG. 47 can't be used for a chain type Band;

DETAILED DESCRIPTION

In order to fully understand the scope of the teachings herein for creating permanent jewelry, various specific examples will be provided with the understanding that such teachings can be broadly applied to bracelets, bangles, anklets, necklaces, chokers, or rings whether chain, wire (solid or hollow), jewelry sheet or bar stock and irrespective of the cross sectional or peripheral shape thereof, the cross section (solid or hollow) and peripheral shape, the material (e.g., solid gold, solid silver, sterling silver, gold or silver plate, etc.) as well as the choice of chain or wire being a matter of design choice and aesthetics, and independent of the claimed inventions herein.

For simplicity, as used herein throughout, the term "Band" means, and is intended to mean, individually and collectively, any length of precious metal jewelry chain, jewelry wire (solid or hollow), precious metal sheeting or bar stock (solid or hollow), or any other type of precious metal or precious metal plated material, as well as, in some implementations, stainless steel chain, wire, sheeting or bar stock, that can be part of the loop of a bracelet, bangle, anklet, necklace, choker, or ring.

FIG. 1 illustrates, in simplified form, an example of bangle bracelet 100 for a wrist incorporating one aspect of the teachings herein. As shown in this example, for simplicity, the bangle bracelet 100 is made up of a Band, in this example, solid wire 102 of a precious metal, and having a thickness (e.g., diameter) "t" that is shaped into a partial loop (e.g., circle or oval). As shown, the surface 104 is

smooth and unadorned, however, it is to be understood and appreciated that the surface 104 could be textured or otherwise adorned in some known manner. The bangle bracelet 100 further includes, in this example, a pair of through holes 106a, 106b. The through holes 106a, 106b will be used to join the ends 108a, 108b of the bracelet 100 while on a wearer's wrist and, thereby form a permanent bracelet.

FIG. 2 illustrates, in simplified form, a perspective view of another permanent jewelry component in accordance with the teachings herein, in the form of a tube bar 200. As shown, the tube bar 200 involves a body (typically involving, in whole or part a precious metal, such as gold, silver or platinum, but may also be made of nickel or a precious metal plated base metal) having a pair of through holes 202a, 202b passing through from one side of the outer surface 206 of the body to the other (i.e., entirely through the tube bar 200), and is sized to correspond to the through holes 106a, 106b of the bangle bracelet 100. In addition, the tube bar 200 includes a cavity 204 of a size "t+" (i.e., it is sized slightly larger than the ends 108a, 108b of the bangle bracelet 100) so that an end 108a, 108b of the bangle bracelet 100 can be inserted therein to at least an internal depth such that the respective through holes 106a, 106b, 202a, 202b align. Depending upon the particular implementation, the cavity 204 need not, or can, extend entirely through the tube bar 200.

As shown, the tube bar 200 is depicted as curved, with a curvature radius corresponding to that of the bangle bracelet 100. However, it should be understood and appreciated that other implementations of the tube bar 200 can have a different radius of curvature, it can be straight, or it can have any other shape (overall or in cross section), depending upon its intended prominence and the Band to which it will be attached.

FIGS. 3-6 respectively illustrate, in simplified form, for purposes of understanding, a top view (FIG. 3) (the bottom view being a mirror image thereof), a right side view (FIG. 4) (the left side view being a mirror image thereof), a back view (FIG. 5) and a front view (FIG. 6) of the tube bar 200 of FIG. 2.

To form the permanent jewelry item, in this example, a permanent bangle bracelet, the Band forming the bangle bracelet 100 and tube bar 200 are joined in the following steps, bearing in mind that, unless inherently necessary, certain steps may be performed in a different order or combined.

FIGS. 7-12 illustrate, in simplified form, one example sequence for creating a permanent bangle bracelet using the Band for the bangle bracelet 100 of FIG. 1 and tube bar 200 of FIG. 2.

In this regard, as shown in FIG. 7, the end 108a is slid into the cavity 204 of the tube bar 200 until the respective through holes 106a, 202b are aligned.

As shown in FIG. 8, a pin 800 sized to snugly fit within the through holes 106a, 202b is inserted through the through holes 106a, 202b. The pin 800 has a length (not to scale) such that it extends beyond both side of the outer surface 206 of the tube bar 200. Typically, the pin will be made of the same material as the tube bar 200. However, optionally, for aesthetic contrast, the pin 800 can be selected to contrast with the tube bar, 200. For example, as an aside, the tube bar 200 could be one of plain gold, rose gold or white gold, and the pin 800 could also be selected so that it was plain gold, rose gold or white gold to match the tube bar 200. Alternatively, if the tube bar 200 was plain gold, the pin 800 could be rose gold or white gold, if the tube bar 200 was rose gold,

the pin **800** could be plain gold or white gold, or if the tube bar **200** was white gold, the pin **800** could be plain gold or rose gold.

As a further aside, optionally at some part of the process prior to the final joining, an adornment, for example a charm **802**, can be inserted onto the bangle bracelet **100**.

As shown in FIG. 9, the pin **800** is then compressed **900** to lock the bangle bracelet **100** and tube bar **200** together, for example, the pin **800** can be peened using a plate inserted between the wearer and the portion of the pin **800** between the wearer and the tube bar **200** and hitting the opposite end of the pin **800** with a small hammer (not shown), or the pin **800** can be crimped, for example, using a pair of parallel jaw pliers **902**. Optionally, if parallel pliers are used, it is desirable to have some form of depth stop **904**, for example an adjustable screw or stop block, to limit the crimping of the pin **800** and thereby avoid damaging or deforming the tube bar **200**. The peening or crimping compresses and deforms both ends of the pin **800** and ensures that the pin **800** cannot slide out of the aligned through holes of the Band and tube bar **200**.

As shown in FIG. 10, the opposite end **108b** of the Band is then inserted into the opposite end of the tube bar **200**.

As shown in FIG. 11, a pin is inserted as described in connection with FIG. 8, and, as shown in FIG. 12, the pin **800** is then peened or crimped as described in connection with FIG. 9 thereby completing creation of the permanent bangle bracelet **1200**.

Depending upon the particular implementation, in some implementations, the pins **800**, if crimped, could be crimped sequentially, and with other implementations, the pins **800** could both be crimped concurrently with an appropriate tool.

FIG. 13 illustrates, in simplified form, an example of a permanent bangle bracelet **1300** created according to the teachings herein. Note that, as shown, the tube bar **1302** of FIG. 13 (and correspondingly the Band, in this example, a wire **1304**, of the permanent bangle bracelet **1300**), have their through holes placed so that the crimped pins **1306a**, **1306b** are essentially radial to the wrist **1308** of the wearer, as opposed to the permanent bracelet of FIG. 12, where the crimped pins **800** would be essentially longitudinally aligned with the arm **1310** of the wearer.

The process is essentially the same to create an wrist bracelet, ankle bracelet, necklace, choker or ring, the only difference being overall size and size of the components.

As should now be appreciated, advantageously, using the foregoing process, there is no need for any welding apparatus, and the process easily can be completed with minimal training and skill compared to micro welding.

Having described an example of the process for creating permanent jewelry, some representative different variants will now be described, with the understanding that a myriad of different variants can be created according to, and without deviating from, the teachings herein.

For example, advantageously, tube bars need not be plain, such as shown in FIGS. 2-6. Variant tube bars can themselves have different adornments.

For example, FIGS. 14-18 respectively illustrate, in simplified form, different views of a tube bar **1400** that includes one or more adornments **1402** raised above the surface **1404** of the tube bar **1400**.

More particularly, FIG. 14 is a perspective view of this example type tube bar **1400**, FIG. 15 is a top view of the tube bar **1400** of FIG. 14 (with bottom being a mirror image thereof), FIG. 16 is a right side view of the tube bar **1400** of FIG. 14 (with the left side being a mirror image thereof), FIG. 17 is a back view of the tube bar **1400**

of FIG. 14, and FIG. 18 is a front view of the tube bar **1400** of FIG. 14. Although the adornments are shown as simple hoops, any of a myriad of adornments, raised above the surface **1404**, can be created, in some cases simply resulting in a raised texture on the tube bar **1400**.

Of course, adornments need not be raised above a surface of the tube bar. Advantageously, example adornments can be added into a surface of the tube bar as well.

FIGS. 19-24 respectively illustrate, in simplified form, different views of another tube bar **1900** that includes one or more adornments **1902** into (i.e., below) the surface **1404** of this tube bar **1900**, for example, as shown, in the form of an engraved word.

More particularly, FIG. 19 is a perspective view of this example tube bar **1900**, FIG. 20 is a top view of the tube bar **1900** of FIG. 19, FIG. 21 is a bottom view of the tube bar **1900** of FIG. 19, FIG. 22 is a right side view of the tube bar **1900** of FIG. 19 (with the left side being a mirror image thereof), FIG. 23 is a back view of the tube bar **1900** of FIG. 19, and FIG. 24 is a front view of the tube bar **1900** of FIG. 19. Although the adornments are shown as letters, any of a myriad of adornments that are etched or engraved or otherwise recessed into the surface can be created, in some cases again resulting in a surface texture for the tube bar **1900**.

FIGS. 25-32 illustrate, in simplified form, different views of yet another example of a type of tube bar **2500** containing one or more raised adornments **2502**, in this case, one or more raised ring portions to which some other element, for example a charm, a chain, a pendant, etc., may be attached.

More particularly, FIG. 25 is a perspective view of this example tube bar **2500**, FIG. 26 is a top view of the tube bar **2500** of FIG. 25, FIG. 27 is a bottom view of the tube bar **2500** of FIG. 25, FIG. 28 is a right side view of the tube bar **2500** of FIG. 25, FIG. 29 is a left side view of the tube bar **2500** of FIG. 25, FIG. 30 is a back view of the tube bar **2500** of FIG. 25, FIG. 31 is a front view of the tube bar **2500** of FIG. 25, and FIG. 32 is the perspective view of FIG. 25 showing how an example charm might be attached to the tube bar **2500**.

Finally, it should be appreciated that adornments are not confined to being exclusively raised above, or recessed into, the surface **1404** of a tube bar. Adornments that are partially raised above and partially below the surface **1404** can also be present.

FIGS. 33-39 illustrate, in simplified form, different views of yet another example of a tube bar **3300** that includes adornments **3302**, in the form of gemstones, that are partially above and partially below the surface **1404** of the tube bar **3300**.

More particularly, FIG. 33 is a perspective view of this example type tube bar **3300**, FIG. 34 is a top view of the tube bar **3300** of FIG. 33, FIG. 35 is a bottom view of the tube bar **3300** of FIG. 33, FIG. 36 is a right side view of the tube bar **3300** of FIG. 33, FIG. 37 is a left side view of the tube bar **3300** of FIG. 33, FIG. 38 is a back view of the tube bar **3300** of FIG. 33, and FIG. 39 is a front view of the tube bar **3300** of FIG. 33. As best illustrated in ghost lines in FIGS. 38-39, a portion **3802** of the gem stones **3302** are raised above the surface **1404**, and another portion **3804** of the gem stones **3302** are below the surface **1404**.

Up to now, the various examples shown have involved a tube bar into which a Band that forms a part of the permanent jewelry is inserted. However, the instant approach is not so limited. For example, in some cases, the permanent jewelry may be made using Band material that,

in cross section is hollow (i.e., it is a tube), irrespective of whether the outer cross section is round, oval, square, rectangular, hexagonal or any other shape, and whatever the cross section of the hollow is. Advantageously, a reverse version the approach described above can be used with such a Band as well and, even more advantageously, can help ensure proper alignment between the ends to be joined.

FIG. 40 illustrates, in simplified form, one example 4000 illustrating a reverse version for creating an item of permanent jewelry according to the teachings herein. As shown in FIG. 40, there are two ends 4002a, 4002b of the Band, in this example, hollow wire or bar stock (only a portion of which is shown), to be joined to form an article of permanent jewelry (which, as shown for simplicity, is round, but could be of other shaped cross sections as noted above). In accordance with the foregoing teachings, each end of the Band has through holes 106a, 106b therein. An internal bar 4004 having through holes 4006a, 4006b (of the same size as the through holes 106a, 106b) is provided whose maximum outer dimension, in the largest direction, is slightly less than the hollow portion 4008a, 4008b of the ends 4002a, 4002b of the wire or stock, such that it can slide into the hollow portions 4008a, 4008b of the ends 4002a, 4002b. The internal bar 4004 is constructed such that, when the terminal surfaces 4010a, 4010b of the ends 4002a, 4002b of the Band abut, the respective through hole pairs 106a, 4006a, 106b, 4006b are aligned such that a pin 800 (not shown) in this view can be inserted therein and peened or crimped to thereby join the two ends 4002a, 4002b in proper alignment and without any of the type of marring that would arise from micro welding.

FIG. 41 illustrates, in simplified form a magnified longitudinal cross section 4100 of the ends 4002a, 4002b of FIG. 40 through the pin center axis after the ends 4002a, 4002b of FIG. 40 have been joined. As can be seen in this view, the crimping/peening as described above caused the pin ends to expand 4102 beyond the edges of the outer through holes 106a, 106b and thereby prevent the pin 800 from sliding out.

Up until now, all of the examples have involved tube bars having two through holes for pins. However, some implementations can readily be constructed that only require the tube bar to have one through hole.

FIG. 42 illustrates, in simplified form, an example implementation involving a tube bar that only includes one through hole.

As shown in FIG. 42, there is portion 4200 of a Band that will form an item of permanent jewelry and a tube bar 4202 similar to what has been previously described (i.e., the tube bar 4202 could be plain, include adornments, be curved or straight). However, unlike the previous tube bars, this tube bar only has one through hole 4204, which will be used to join the portion 4200 of the Band to another portion of the intended permanent jewelry item.

In contrast to most of the previous examples, this tube bar 4202 has been joined to the portion 4200 while not on the intended wearer. As such, with this example implementation, the tube bar is partially joined at one end 4206 to a terminal end of the portion 4200 by a joint 4208, using a known soldering technique or through micro welding, since, not being on the intended wearer, its entirety is readily accessible. Thus, for example, this process could be performed in a jewelry manufacturing facility or jewelry store well prior to selection by any intended wearer (optionally including sufficient excess length of wire/stock that can be cut down for a potential wearer (assuming the capability to add an appropriate through hole thereafter)). Of course, a potential disadvantage of such an approach is that, in cases

where the joint 4208 has been previously made, the process may eliminate the possibility of an intended wearer opting for a different combination of Band and tube bar. Of course, in other cases, the intended wearer could individually select the two (i.e., Band and tube bar), and then, thereafter, they would be joined remote from the intended wearer and, later, once completed, the other end of the Band could be affixed to while on the intended wearer to complete the item of permanent jewelry using the through hole and pin approach described above.

As noted above, advantageously the tube bar between the two through holes, or through hole and opposite end if of the type shown in FIG. 42, is not limited to any particular shape. For example, FIG. 43A illustrates, in simplified form an alternative example tube bar 4300a that has ends 4302a, 4302b that are similar to those previously described, including internal orifices 4304 to accommodate the Band and through holes 202a, 202b to accommodate pins (not shown), however, as shown the body 4306a of the tube bar 4300a between the two through holes 202a, 202b has a large shape and incorporates an adornment 4308, as shown, a single jewel.

FIG. 43B illustrates, in simplified form another alternative example tube bar 4300b similar to that of FIG. 43A except that it has a body 4306b of a different shape and a different adornment 4308b in the form of an enamel filled surface engraving.

FIG. 43C illustrates, in simplified form yet another alternative example tube bar 4300c, similar to that of FIG. 43A, except that it has a body 4306c of another different shape, in this case, two pieces of hollow square bar stock joined at an angle (which could be any angle).

Thus, from FIGS. 43A-43C, it should be understood and appreciated that the tube bar can be of any of a myriad of different overall shapes, including, for example, letter(s), number(s) symbol(s) or any combination thereof, the particular overall shape of the body between within the through holes being purely a matter of design choice.

FIG. 44 illustrates, in simplified form, another example implementation of an item of permanent jewelry 4400 that can be created by applying the teachings herein using a variant the foregoing. As shown, this permanent jewelry 4400 is circular and made up of multiple segments 4402a, 4402b, 4402c of Band coupled together using multiple tube bars 4404a, 4404b, 4404c. As such, the Band segments can be of similar or different materials and/or different colors/textures of the same material, for example, as shown, one segment 4402a could be yellow gold, another segment 4402b could be white gold and the third segment 4402c could be grey gold or spangold, with same being true for the tube bars 4404a, 4404b, 4404c. Similarly, one of the segments 4402a could be chain, whereas another 4402b could be wire and the third, 4402c could be either of the foregoing. Thus, using multiple segments allows for tremendous design flexibility, not as readily possible for conventional permanent jewelry.

FIG. 45 illustrates, in simplified form, yet another example implementation of an item of permanent jewelry 4500 that can be created by applying the teachings herein using a variant the foregoing, in this case, the single pin tube approach of FIG. 42. As shown in FIG. 45, multiple segments 4502a, 4502b, 4502c of a Band are joined using tube bars 4504a, 4504b, 4504c having different radii of curvature, to create an oval shaped item of permanent jewelry 4500.

FIG. 46A illustrates, in simplified form, a top view of another example implementation of an item of permanent jewelry 4600 that can be created using a variant the fore-

going. FIG. 46B illustrates, in simplified form, a side view of the item of permanent jewelry 4600 of FIG. 46A viewed from the direction shown by the arrow A in FIG. 46A.

As shown in FIGS. 46A-46B, this permanent jewelry 4600 is made from a Band involving rectangular stock 4602 (solid or hollow) having a height ("h") that is smaller than its width ("w") fashioned in the shape of a hexagon. As shown, at least one correspondingly rectangular tube bar 4604a is used to join ends of the Band 4602 to form this permanent jewelry 4600 using pins 800 as described previously. Optionally, for certain shapes, for example to avoid deforming them, it will be desirable to use more than one tube bar 4604b (as shown using ghost lines).

Moreover, as evident by comparing the two tube bars 4604a, 4604b in FIGS. 46A-46B, it should again be reinforced and appreciated that the direction of the pins 800 can be oriented such that they will be oriented outward from the portion of the wearer's body where the permanent jewelry will be affixed, or, alternatively, along the portion of the wearer's body where the permanent jewelry will be affixed, or, even along some other orientation, the particular orientation being a matter of design choice.

Bands of the chain type can, in some cases, present issues that differentiate them in some respects from other types of Band material. Advantageously, through a slight modification, the foregoing pin-joiner approaches can still be used.

FIG. 47 illustrates, in simplified form, an additional example variant implementation of a tube bar 4700 (only a portion of which is shown) suitable for use with a chain-type Band. As shown, the tube bar 4700 includes a through hole 202a as discussed previously, but also includes a slot 4702 in a plane perpendicular to the longitudinal direction of the through hole 202a. The slot 4702 has a spacing "S" of an extent suitable to allow a link of a chain to pass into the tube bar 4700 and a depth "d" that will enable a pin 800 inserted through the through hole 202a to lock the chain to the tube bar 4700.

FIG. 48 illustrates, in simplified form, a top view of one representative example of how a chain-type Band 4800 can be attached to a tube bar 4700 as part of the process or forming an item of permanent jewelry. In this example, the Band 4800 is a fine chain such that, when a terminal link 4802 of the chain 4800 inserted into the slot 4702 tube bar 4700, the through hole 106a of the Band 4700 is the open portion within the link 4802. As a result, a pin (not shown) inserted into the through hole 202a and peened or crimped as described above will lock the link of the Band 4800 within the tube bar 4700.

FIG. 49 illustrates, in simplified form, a top view of another representative example of how a chain-type Band can be attached to a tube bar as part of the process or forming an item of permanent jewelry. In this example, the Band 4900 (only one link 4902 of which is shown) has larger chain links, so it is possible to take a terminal link 4902 and incorporate a through hole 4904 in the terminal link 4902 (which will serve as the Band through hole 106a) whose diameter corresponds to that of the through hole 202a of the tube bar 4700. As a result, a pin 800 (not shown) inserted into the through hole 202a and peened or crimped as described above will similarly lock the link 4902 of the Band 4900 within the tube bar 4700.

Despite the foregoing, in some cases, the approach of FIGS. 48-49 may not be feasible, either because of the size of the slot 4702 that would be required for a particular chain-type Band, or because of the specific links making up the Band, particularly the terminal link of the Band. Nev-

ertheless, the approach can still be used through implementations similar to the one which will now be described in connection with FIG. 50.

FIG. 50 illustrates, in simplified form, a representative example of an implementation variant that can be used in circumstances where the tube bar 4700 of FIG. 47 can't be used for a chain type Band. Nevertheless, as will be seen, tube bars as previously described can be used.

As shown, by way of example, a plain tube bar 200 as discussed above can be used with this example implementation. However, due to the type of links of the Band 5000, in order to attach the Band 5000 to the tube bar 200, a terminal link 5002 of the Band will get attached to an adapter bar 5004 made up of a jump ring 5006 and a plug 5008, sized to fit into the cavity 204 of the tube bar 200, with the plug 2008 having a through hole 5010 that corresponds to the through hole 202a, 202b of the tube bar 200. The jump ring 5006 is used to connect the terminal link 5002 to the plug 5004.

As a result, to attach the Band 5000 to the tube bar 200, the plug 5004 is inserted into the cavity 204 with the through holes 202a, 5010 aligned. Once that is done, a pin 800 is inserted through the aligned through holes 202a, 5010 and crimped/peened as described above.

Should the need arise to remove an item of permanent jewelry constructed according to the teachings herein from a person (for example, for a temporary medical reason or otherwise), this can advantageously be accomplished by simply removing one end of a connecting pin and sliding the pin out via the other end. In this way, there is no need to damage the tube or Band to do so. Moreover, thereafter, the item of permanent jewelry can be re-attached simply through use of a new pin.

As should now be appreciated, some variants applying the teachings herein allows for the creation of items of permanent jewelry that can eliminate the need for micro welding.

Applying the teachings herein with other variants allows for the creation of items of permanent jewelry that involve Bands of heavier material than can be created according to conventional methods.

Applying the teachings herein can avoid or minimize the need for special skill or training in order to create items of permanent jewelry.

Moreover, the teachings, components and processes herein are scalable in size such that they can be used to create small items of permanent jewelry, like rings, larger items of permanent jewelry, like bracelets, anklets or bangles, or even larger items of permanent jewelry like necklaces using essentially the same approaches and types of components.

Applying the teachings herein thus can make it possible to create items of permanent jewelry that could not be created at all using conventional micro welding approaches.

Some variants applying the teachings herein can ensure perfect alignment between two ends of a Band.

The foregoing outlines, generally, the features and technical advantages of one or more implementations that can be constructed based upon the teachings in this disclosure in order that the following detailed description may be better understood. However, the advantages and features described herein are only a few of the many advantages and features available from representative examples of possible variant implementations and are presented only to assist in understanding. It should be understood that they are not to be considered limitations on the invention as defined by the appended claims, or limitations on equivalents to the claims. For instance, some of the advantages or aspects of different

11

variants are mutually contradictory, in that they cannot be simultaneously present in a single embodiment. Similarly, some features or advantages may be applicable to one aspect and inapplicable to others. Thus, the foregoing features and advantages should not be considered dispositive in determining equivalence. Additional features and advantages, although not detailed herein, will be apparent from the teachings of the description, drawings, and claims.

What is claimed is:

1. An item of permanent jewelry comprising:
a Band including a first terminal end and a second terminal end, wherein the first terminal end includes a through hole therein;
a tube bar having at least one through hole corresponding to the through hole of the first terminal end and a cavity defined by a surface of the tube bar;
wherein the first terminal end is located within the cavity of, and wholly surrounded therewithin by, the tube bar such that the through hole of the first terminal end and through hole of the tube bar are aligned;
a pin, extending through the aligned through holes of both the Band and tube bar, wherein the pin is compressed on both sides of the aligned through holes such that the pin cannot slide out of the aligned through holes;
wherein the second terminal end of the Band is coupled to the tube bar such that a closed loop involving the Band and tube bar is formed.
2. The item of permanent jewelry of claim 1, wherein the tube bar includes an adornment.
3. The item of permanent jewelry of claim 1, wherein the pin is a first pin and the second terminal end of the Band is coupled to the tube bar via a second pin.
4. The item of permanent jewelry of claim 1, wherein the second terminal end of the Band is coupled to the tube bar via one of solder or a micro welded connection.
5. The item of permanent jewelry of claim 1, wherein the tube bar is a first tube bar of at least two tube bars wherein: the Band comprises at least two segments,
a first of the at least two segments has a first end coupled to one of the at least two tube bars via a first pin, and a second end coupled to an other of the at least two tube bars;
a second of the at least two segments has a first end coupled to an other of the at least two tube bars via a second pin;
a second end of the first of the at least two segments is coupled to the other of the at least two tube bars; and a second end of the second of the at least two segments is coupled to the one of the at least two tube bars; wherein the at least two segments and at least two tube bars collectively form a closed loop.
6. An item of permanent jewelry comprising:
a Band including a first terminal end and a second terminal end, wherein the first terminal end includes a through hole therein;
a tube bar having at least one through hole corresponding to the through hole of the first terminal end;
wherein the first terminal end is located within a cavity of the tube bar such that the through hole of the first terminal end and through hole of the tube bar are aligned;
a pin, extending through the aligned through holes of both the Band and tube bar, wherein the pin is compressed on both sides of the aligned through holes such that the pin cannot slide out of the aligned through holes;

12

wherein the second terminal end of the Band is coupled to the tube bar such that, when joined and on a wearer, a closed loop involving the Band and tube bar is formed such that the closed loop cannot be removed by the wearer without damaging at least one of the Band, the tube bar or the pin; and

wherein:

the Band comprises at least one link of a chain; and the tube bar includes a slot within which a portion of the at least one link is contained.

7. The item of permanent jewelry of claim 6, wherein: second terminal end of the Band is coupled to the tube bar by one of a microweld or a solder connection.

8. An item of permanent jewelry comprising:
a Band; and
a tube bar including a cavity into the tube bar, the cavity being entirely defined by a surface of the tube bar and dimensioned to fully surround a terminal end of the Band inserted therein;

wherein the Band is connected to the tube bar by at least one crimped pin extending through both the tube bar and an end of the Band so that the Band and tube bar collectively form a closed loop about a part of a person of a size such that the closed loop cannot be slid off the person without damaging at least one of the Band, the tube bar or the crimped pin.

9. The tube bar of claim 8 further comprising:
an adornment.

10. The tube bar of claim 9, wherein the adornment extends, at least in part, outward from a surface of the tube bar.

11. The tube bar of claim 9, wherein the adornment extends, at least in part, into a surface of the tube bar.

12. A method of forming an item of permanent jewelry on a person, the method comprising:

- a) coupling a first end of a Band to a tube bar;
  - b) placing the Band about a portion of the person;
  - c) coupling a second end of the Band to the tube bar using a pin so as to form a closed loop about the portion;
  - d) compressing the pin so that the pin cannot slide out of the tube bar; and
- wherein the compressing in step "d)" comprises at least one of: (i) crimping the pin using parallel jaw pliers while the Band is on the portion of the person, or (ii) peening the pin while the Band is on the portion of the person.

13. The method of claim 12, wherein step "b)" occurs before step "a)" in time.

14. The method of claim 12 wherein step "a)" occurs before step "b)" and the coupling in step "a)" includes one of:

soldering the Band to the tube bar or micro welding the Band to the tube bar.

15. The method of claim 12 further comprising:
prior to step "c)" attaching at least one adornment to the Band.

16. The method of claim 12 wherein the Band includes a chain having links and, wherein:

the coupling in step "a)" further comprises connecting a terminal link of the chain to a jump ring of an adapter bar; and inserting a plug of the adapter bar, having a through hole into the tube bar such that the through hole of the plug and a through hole of the adapter bar are aligned and the pin is inserted through the through hole of the plug and the through hole of the adapter bar.
